CABLE TERMINAL FOR IGNITION SYSTEMS

Antoine T. H. Fontaine, 12a Dr. Zamenhofstraat,
Rotterdam, Netherlands

Filed Aug. 24, 1960, Ser. No. 51,737

Claims priority, application Netherlands Aug. 29, 1959
6 Claims. (Cl. 315—54)

This invention relates to filter circuits and particularly to means for suppressing high frequency currents in any system where they are not desired, one instance being an ignition system for internal combustion engines for airplanes, automobiles and the like.

An object of the invention is to reduce interference to sensitive measuring or signalling apparatus such as radio receivers, due to the higher frequency components that may be present in any conductors within range of the apparatus, and specifically those generated by ignition systems during the sparking action.

It is well known that the voltage wave in a spark plug conductor increases rapidly until the spark gap is broken down and then decreases rapidly. As this wave is not sinusoidal but rich in the higher harmonics, these higher frequency components generated are picked up by adjacent radio receiving apparatus. The harmonics produce in the receiver units a sputtering sound sufficient to seriously interfere with radio reception.

Heretofore such methods as shielding the entire engine or only the ignition system have been tried and these methods have proved too inconvenient and bulky. Also filter systems have been used, these systems necessitating special coils and condensers which increase the weight of the motor element and the space required per horse power.

The present invention combines the effectiveness of the shield and filter methods with substantially no change in weight, space and convenience from the ordinary ignition wiring system.

In one embodiment the invention provides a cable termination for ignition systems providing a high degree of protection against the disturbances discussed and commonly occasioned by sparks in the ignition system. The frequency region concerned is particularly that about 40 megacycles, being the important region in connection with radio and television traffic.

It is one object of the invention to construct this cable termination from coil sections in such a manner as to constitute series capacities in the relevant frequency range by inserting the entire coil in a screen of attenuating material such as ordinary plain commercial thin plate iron, with respect to which the sections possess partial natural capacities resulting in a filter made up of π sections having practically no direct current resistance and functioning as connection between the end of the cable and a conductor terminating in a spark gap as used in ignition systems.

It is a feature of the invention to provide the termination in connection with spark gaps in sparking plugs of internal combustion engines.

It is another feature of the invention to provide the termination in connection with spark gaps occurring in a distributor of an ignition system.

The filter is active above its resonance frequency as a capacitive voltage divider for the suppression of interference.

It is an object of the invention to suppress interference from the operation of systems involving spark discharges by providing a material at a definite point which attenuates by eddy current losses currents induced by spark discharges in an extensive system.

It is another object of the invention to provide an inter-

ference suppressor of the type considered in the shape of a plurality of current sections in series relation in an absorbing sleeve such as to constitute a π_m filter for insertion at a definite point adjacent a spark gap.

5 A better understanding of the invention will be had from the detailed description to follow, in connection with the attached drawing in which

10 FIGURE 1 is a view of the screening of a spark plug in a first embodiment of a filtering cable terminal obtained by building coil sections into a cap for a sparking plug;

FIGURE 2 is the basic form of the filter;

FIGURE 3 is a filter diagram;

15 FIGURE 4 is a family of curves characteristic for the action of the filter of FIG. 3;

FIGURE 5 is an idealized curve taken from this family;

FIGURE 6 is a diagram illustrative of the action of the filter of FIG. 3 above the resonance frequency of FIG. 5;

20 FIGURE 7 is a section of a practical suppressor with shield as shown in FIG. 1; and

FIG. 8 is a sectional view taken along line VIII—VIII of FIG. 7 with a part broken away.

25 The invention initially considers a normal metallic spark plug cap with extended nozzle as shown in FIG. 1 and consisting of a shell 1 fitting closely on a spark plug and having a nozzle 2 enclosing a pin 3 clamping the spark plug conductor or cable C.

30 The spark cable C is connected to the pin 3 by pressing the cable into the nozzle (see also FIG. 7).

I have found that the suppressing effect of a normal metal plug cap in itself is quite small, for which reason I provide filter sections by replacing the direct connection 35 between the pin 3 and the plug conductor by a coil 5 (see FIG. 7) made up of sections and having practically no resistance. The sections all lie within the screening shell 1, with regard to which they present natural capacities, resulting in the presence in the connection from the cable 40 to the spark gap, of a low-pass filter made up of π_m sections.

The basic form of this low-pass filter is shown in FIGURES 2 and 3, whereas FIG. 4 gives an extract from a family of curves for these filters showing the region important for the present purpose, mainly consisting of suppression in the region between 40 and 240 megacycles, though it is also active at higher frequency, at least up to 800 megacycles, compare FIG. 6 showing the basic form of the same filter at higher frequency.

45 Moreover the filter also has a suppressing action at higher radio frequencies below 40 megacycles.

FIG. 4 shows the attenuation in decibels db as a function of the normalized or resonant frequency with the quantity m (i.e. the ratio of series and shunt capacities) as parameter. The quality Q of a coil section 55 is supposed to be infinite. In a practical case Q will be small resulting in the dotted graph.

FIG. 5 shows the behaviour of the filter.

FIG. 7 shows a section of a plug cap according to the 60 invention in two mutually orthogonal directions, showing at 1 the lug shell over a spark plug P, at 2 the nozzle, at 3 the conducting pin protruding from the nozzle 2 to contact the cable C core W, at 4 the clamp for gripping the plug conductor, at 5 the coil wound on a grooved cylinder 6 of refractory insulation and at 7 the insulating body in the shell supporting the internal parts and the coil.

65 It is a feature that the provision of the subtle means described at the relevant point in the ignition circuit constitutes an effective suppression by repeated voltage division in consecutive sections, each of which in itself only provides small attenuation.

It will be understood, of course, that the disclosure herein has been to a particular means for carrying out the invention, but the appended claims are intended to cover such equivalent combinations as the state of the art will allow.

What is claimed is:

1. In an ignition system for internal combustion engines having
  - (A) a spark plug,
  - (B) a source for energizing said plug,
  - (C) a conductor between said plug and said source, and
  - (D) an element for absorbing parasitic frequencies from the sparks produced by said plug, said element being connected between said plug and said conductor and comprising:
    - (1) a series of coil sections with low direct current resistance, and
    - (2) a grounded metallic sheath having inherent losses surrounding said coil,
2. An element according to claim 1 wherein said coil comprises an insulated cylinder having spaced circum-

ferential grooves therealong each of which contains a coil section.

3. An element according to claim 1 wherein said grounded metallic sheath is grounded by being connected to the outside of said spark plug.

4. A cable terminal for absorbing parasitic frequencies from spark gaps comprising:

- (a) a sectionalized series coil with low direct current resistance;
- 10 (b) a grounded metallic sheath having inherent losses surrounding said coil;
- 15 said coil and sheath constituting, in a range of frequencies above the resonant frequencies of the coil sections, a capacitive voltage divider by reason of the capacitance of the coil sections in longitudinal branches and of the distributed capacitance of the coil sections with respect to said metallic surrounding sheath, which at frequency below resonance acts as an *m*-derived low pass filter having coil sections of low quality.
- 20 5. A terminal according to claim 4 in which the natural resonant frequency of said sectionalized coil lies below the lowest frequency of the suppression region.
6. A terminal according to claim 4 wherein said coil comprises an insulated cylinder having spaced circumferentially grooves each of which contains a coil section.
